UNITED STATES PATENT OFFICE.

HOWELL RINGGENBERG, OF SHERBURN, MINNESOTA.

VACUUM TANK.

Application filed October 18, 1924. Serial No. 744,415.

To all whom it may concern:

Be it known that I, HOWELL RINGGENBERG, a citizen of the United States, residing at Sherburn, in the county of Martin and State of Minnesota, have invented certain new and useful Improvements in a Vacuum Tank, of which the following is a specification.

This invention relates to an improved vacuum tank designed to be installed in the fuel feeding system of an automobile to act in the customary and well known manner.

It is my object to generally improve upon tanks of this class by providing one which is structurally different from patented and marketed vacuum tanks with which I am familiar, the present improved tanks having been carefully designed to insure effectiveness of operation of the fuel feeding system.

More specifically speaking, I propose to provide an improved device of this kind which embodies a tank having an upper vacuum chamber, this tank being closed by a removable cover which carries the essential details of the device, the cover and these details being removable as a single unit.

It is also a feature of the invention to equip the cover with a depending internally disposed bracket which carries a float controlled bell crank equipped with a single spring pressed valve for alternately closing the air vent and the passage leading to the intake manifold.

In the accompanying drawing:—

The figure represents an enlarged view partly in section and partly in elevation showing the improved structure with the parts in their normal position.

Referring to the drawings in detail, the reference character 1 designates an open top tank having a drain plug 2 at its bottom and a coupling for a supply pipe 3 which is adapted to lead to a carburetor (not shown). In the upper portion of this tank is a suitably designed vacuum chamber 4. Depending from this chamber into the fuel containing chamber is a curved discharge pipe 5 provided with a suitably designed well known check valve 6. The upper end of the tank is closed by a removable cover 7 detachably bolted or otherwise secured to a flange at the top of the tank. Appropriate packing 8 is utilized here to provide a fluid tight joint. Connected to the under side of the center of the cover and depending into the vacuum chamber is a substantially L-

shaped bracket 9. Pivoted to the free end of the short arm of this bracket is a bell crank 10 carrying a vertically disposed spring containing cup 11 in which a coil spring 12 is located. Also disposed within this cup is a ball check valve 13. Normally, this ball check valve closes the lower end of a short pipe 14 which is adapted to communicate with the intake manifold of the engine. Under normal conditions however, the ball and check valve is adapted to close a port 15 formed at the inner end of an air vent pipe 16.

To insure proper seating of the valve, a stop 17 is provided on the pipe adjacent the port 15. The float 18 serves to control the ball check valve, the same being provided at its bottom with a guide stem 19 adapted to telescope into the pipe 5 and being provided at its top with a stem 20 having stop shoulders 21 located thereon at spaced points for cooperation with the bell crank. If desired, the brackets, pipes 14 and 16, and the other cooperating details may all be carried by the removable cover so as to be removed therewith as a unit. Also connected to and removable with the cover is a pipe 22 which is adapted to be connected with a gasoline supply tank. If desired, the discharge end of this pipe 22 may be screened as indicated at 23.

Assuming that the lower compartment of this tank and lower portion of the vacuum chamber are filled with gasoline to the normal fuel line, the float 18 will assume the approximate position indicated in the drawing. At this same time, the valve cup 11 will be in a vertical position as seen, and the cup 13 will close the intake manifold pipe 14. Atmospheric air will enter through the vent 16 and will permit the gasoline to flow by gravity from the compartment 4 and chamber beneath it through the pipe 3 to the carburetor. Now, if for any reason the fuel level should drop, the float will go down with it and when an unsafe level is reached, the stop 21 on the upper end of the stem 20 will abut the short arm of the bell crank 10, rocking the latter upon its pivot and swinging the cup 11 to a diagonal position, at which time the ball check valve will be projected to close the port 15, cutting off outside air. Obviously, the suction then produced in the chamber 4 through the intake pipe 14 will serve to act on the gas supply pipe 22 in the usual way to draw in

additional fuel and to bring fuel in the tank to its normal level again. As soon as the normal level is reached, the parts will assume their original positions.

5 Having thus described the invention, what I claim is:—

1. A vacuum tank for installation in the fuel feeding system of an automobile comprising a tank embodying a cover, a bracket 10 carried by the under side of said cover and depending into the tank, said bracket being of L-shaped formation, a bell crank carried by the free end of the horizontal arm of said bracket, a cup carried by said bell crank, a 15 spring located in said cup, a ball check valve cooperative with said spring and also arranged in said cup, a fuel intake manifold pipe with which said check valve is cooperative, and an air vent controlled by the same 20 valve.
2. A vacuum tank of the class described embodying a substantially L-shaped sup-

porting bracket, a bell crank lever pivoted upon the free end of the short arm of said bracket, a vertically disposed spring containing cup carried by said bell crank, a spring located in said cup, a ball check valve located in said cup and cooperative with said spring, a pipe closed by said ball check valve and adapted to lead to the intake manifold of an engine, an air supply pipe adjacent said first named pipe and provided with a discharge port, a stop on said pipe adjacent said port, the aforesaid ball check valve being adapted to control said port, a float provided at its bottom with a guide stem and at its top with a stem equipped with spaced stops cooperable with horizontal arms of said bell crank for moving said cup to a diagonal position when said float assumes a dangerously low level.

In testimony whereof I affix my signature.

HOWELL RINGGENBERG.
